CUPCAKE CONTAINER

Edward Hildebrand, Jr., Greenwich, Conn., assignor to Chicago Display Company, Melrose Park, Ill., a corporation of Illinois

Filed July 1, 1968, Ser. No. 12,556

Term of patent 14 years

Int. Cl. D9—04

U.S. Cl. D9—189

FIG. 1.

FIG. 2.

FIG. 4.

FIG. 5.

FIG. 3.

FIG. 6.

FIG. 6.

FIGURE 6 is a fragmentary section taken along line 6—6 of FIGURE 1.

I claim:

The ornamental design for a cupcake container, substantially as shown and described.
